UNITED STATES PATENT OFFICE.

OREN F. ROBERTS, OF KANSAS CITY, MISSOURI, ASSIGNOR TO McGEE MANUFACTURING COMPANY, OF KANSAS CITY, MISSOURI, A COMMON-LAW TRUST.

VENDING APPARATUS.

Application filed April 5, 1926. Serial No. 99,830.

My invention relates to improvements in vending apparatus. It is particularly adapted for vending drinks, such as are composed of mixed ingredients, as syrup and carbonated water.

One of the objects of my invention is to provide novel means for accurately measuring and properly apportioning the drink ingredients.

10 A further object of my invention is to provide a novel liquid measuring device, which will automatically and accurately measure and discharge into a receiving receptacle certain liquid ingredients, such as syrups.

15 My invention provides further novel gravity controlled mechanism for accurately controlling the discharge of the other ingredients discharged into the drink receiving and discharging receptacle, whereby a uniform quantity will always be dispensed in a drink.

20 My invention provides further novel motor operated means for actuating the liquid measuring means, and for effecting the tilting of the drink receiving and discharging receptacle, to and from its discharge position.

25 My invention provides further novel means for automatically controlling the operation of the driving motor.

30 My invention provides further novel cam controlled switch mechanism in the motor circuit.

35 My invention also provides an apparatus of the kind described, which is simple, considering its many functions, relatively cheap to construct, which is durable, not liable to get out of order, cleanly, sanitary, accurate and efficient in operation, and which is difficult to fraudulently operate.

40 In the accompanying drawings which illustrate the preferred embodiment of my invention,

45 Fig. 1 is a rear elevation, partly broken away, of my improved vending machine, the rear door being shown opened.

Fig. 2 is a vertical section on the line 2—2 of Fig. 1, the rear door being shown closed.

50 Fig. 3 is an enlarged horizontal section on the line 3—3 of Fig. 1, parts being broken away.

Fig. 4 is a diagrammatic view of the electric circuits controlling the operation of the driving motor.

Fig. 5 is a cross section of the apparatus on the line 5—5 of Fig. 7.

Fig. 6 is an enlarged sectional view on the line 6—6 of Fig. 3.

Fig. 7 is a reduced front elevation of the vending machine.

Fig. 8 is an enlarged rear view, partly in elevation and partly in vertical section, of a portion of the syrup measuring mechanism.

Fig. 9 is a horizontal section on the line 9—9 of Fig. 8.

Fig. 10 is a fragmental sectional view on the line 10—10 of Fig. 12.

Fig. 11 is an enlarged sectional view on the line 11—11 of Fig. 3.

Fig. 12 is an enlarged sectional view on the line 12—12 of Fig. 3.

Fig. 13 is an enlarged sectional view on the line 13—13 of Fig. 12.

Similar reference characters designate similar parts in the different views.

The vending apparatus is provided with a casing 1, which may be of any suitable form and material, and which is shown as being rectangular, and which is provided at its front with a spring closed door 2, which normally closes an opening through which the cups, containing the drinks dispensed, are taken by the purchasers, Figs. 2, 3 and 7.

The front of the casing 1 has attached to it a coin receiving device 3, upon which a coin is deposited and forced by the purchaser into a coin chute 4, Fig. 2. The said coin receiving device may be of any usual type designed for the purpose.

The front of the casing 1 has an opening 5 normally closed by a spring door 6, at the inner side of the casing, for the reception of cups which have been emptied by the purchasers; said opening 5 discharges into a chute 7, which in turn discharges into a large receptacle 8 in the casing 1, which is adapted to hold surplus liquid, which may be spilled in the casing when a purchaser removes a filled cup through the opening 9, normally closed by the door 2, Fig. 6.

The top of the casing 1 has a door 10 normally closing the upper end of a large tank 11 adapted to hold ice, and in which is located a coiled pipe 12 through which carbonated water is adapted to flow. In the tank 11 is disposed a receptacle 13 adapted to hold the syrup which is to form one of the drink ingredients, see Fig. 5.

BEST AVAILABLE COF

1,615,885

The top of the casing 1 has mounted on it a vertical tube 14, Figs. 1, 2 and 6, through which the cups, one of which is shown in Fig. 6, designated by 15, are inserted in 5 nested form into a cup receptacle 16 disposed vertically in the casing at the rear of the front side thereof.

The cup receptacle 16 is provided above its bottom with a cup feeding device of 10 usual type having a horizontally reciprocating lever 17, which when forced rearwardly from the position shown in Fig. 3, will drop a cup 15 from the lower end of the pile of cups, held in the cup receptacle 15 16, onto the bottom of said receptacle, as shown in Fig. 6. When the lever 17 is retracted to the position shown in Figs. 3 and 6, the next succeeding cup of the pile will be in position ready to be dropped when the 20 lever is again forced rearwardly.

Any cup feeding device having such an operating lever will answer my purpose, and as many of such type are on the market no detailed description of the same need be 25 made.

The cup 15 when dropped will be directly at the rear of the door 2, and as the opening 9, which is normally closed by the door 2, communicates with the interior of 30 the cup receptacle 16, the purchaser can readily remove the filled cup 15 through such opening 9.

A drain chute 19, which discharges into the receptacle 8, is supported by the bottom 35 of the receptacle 16, the latter having a drain opening 20 which discharges into the chute 19.

Attached to the rear of the cup receptacle 16 is a funnel 21 the lower end of which is 40 disposed within the receptacle 16 in position for discharging into a cup 15 on the bottom of the cup receptacle 16.

For receiving a measured drink and discharging it into the funnel 21, there is provided 45 an open top drink receiving and discharging receptacle 22, which at its front is provided with a delivery spout 23 adapted, when the receptacle 22 is tilted to the discharge position, shown in Figs. 3 and 6, to 50 empty the contents of the receptacle 22 into the funnel 21.

As shown in Figs. 3 and 6, the drink receiving receptacle 22 is pivoted on a horizontal transverse pin 24 mounted in two 55 lugs 25 on a tiltable frame 26, which in turn is pivoted on two horizontal pins 27 mounted in lugs 28 on a U shaped plate 29, which is supported on a plate 30 mounted on two horizontal transverse channel bars 60 31, the ends of which are supported by opposite sides of the casing 1.

Fastened to the frame 26 is one end of a bar 32 one end of which is threaded and has mounted on it a counterbalancing 65 weight 33, which is adjustable toward and

from the frame 26, and which carries a set screw 34 for securing the weight 33 in its adjusted position. The weight 33 is adjusted to a position such that the outer end of the bar 32 will be swung upwardly when 70 the proper amount for a drink has been deposited, as will be described, into the drink receptacle 22, at which time, by means hereinafter described, the discharge of syrup and carbonated water into the receptacle 22 75 will be shut off, following which the receptacle 22 will be tilted so as to discharge the contents thereof through its spout 23 into the funnel 21, and thence into the waiting cup 15. When the receptacle 22 has 80 emptied, the weight 33 will cause the bar 32 and frame 26 to swing back to the initial position shown in Figs. 1, 3 and 6. The downward movement of the outer end of the bar 32 is limited by its contacting with 85 a plate 35 fastened to the channel bars 31.

The upper end of the cup receiving tube 14 may be provided with a removable cover 36, and the lower end of the coin chute 4 discharges into a coin receptacle 37, Figs. 90 1, 2 and 3.

The rear side of the casing 1 may have a large opening 38 adapted to permit access to the interior of the casing, and normally 95 closed by a door 39.

For supplying carbonated water as one of the ingredients of the drinks vended, one end of the coiled pipe 12, in the tank 11, is connected to a pipe 40, Figs. 1 and 2, which is connected by a usual type of coupling 41 100 with the usual tank 42 containing carbonated water, and having the usual shut off valve 43. By disconnecting the coupling 41, a newly filled tank 42 may be exchanged for an empty one. 105

Connected to the other end of the coil pipe 12 is a conductor 44, which includes a valve casing 45, and which discharges into the top of the drink receiving receptacle 22, Figs. 1, 2 and 3. 110

The valve casing 45 has in it a rotary valve stem 46, which has attached to it a crank 47 adapted when oscillated to open and close the valve. The crank 47 is pivoted to one end of a contractible and extensible coupling comprising a plate 48, to which the crank 47 is pivoted, having slots through which extend clamping screws 49 mounted in a plate 50 which is loosely pivoted to a crank arm 51 fastened on a horizontal transverse rock shaft 52, Figs. 1 and 3, which is pivoted at its ends respectively on two pivot screws 53 and 54 mounted respectively in two plates 30 and 55, the latter being mounted on a bracket 56 supported by the channel bars 31, see Figs. 1, 10 and 12. The loose pivoting of the plate 50, permits the crank 47 to freely oscillate. 115

The rock shaft 52 is oscillated by means of a crank 57 mounted thereon and having two 120 125 130

arms 58 and 59, which respectively extend in different directions, and which are adapted to be consecutively engaged by a roller 60 mounted on a crank arm 61, fastened to a horizontal rotary shaft 62 mounted in the plate 55, Figs. 10, 12 and 13, see Figs. 1 and 3 also.

The shaft 62 has secured to it a worm wheel 63 which meshes with a rotary worm 64, which is secured to a horizontal driven rotary shaft 65, Figs. 12 and 13, which is mounted in the plate 55, and has secured to it a pulley wheel 66, which is connected by a belt 67 with a pulley wheel 68, which is fastened to the armature shaft 69 of an electric motor 70. The motor 70 is mounted on a swinging plate 71 having one end pivoted to a bracket 72 having two upwardly extending arms respectively secured to the channel bars 31, see Figs. 1 and 2.

The other end of the plate 71 is secured to the lower end of a coil spring 73, the upper end of which is fastened to one of the channel bars 31. By this means of support, the weight of the motor retains an operative tension on the belt 67.

For tilting the drink receiving receptacle 22 to the discharge position, shown in solid lines in Figs. 1, 3 and 6, it has secured to it an arm 74, which is in the path of the roller 60. The receptacle 22 normally assumes and retains the filling position, shown in dotted lines in Fig. 6 by gravity. When the crank arm 61 has in its revolution, caused the roller 60 to consecutively engage the arms 58 and 59 of the rock shaft 52, to oscillate the latter, the receptacle 22 will have received and discharged a drink. After leaving the arm 59, the roller 60 engages the under side of the arm 74 and thereby tilts the receptacle 22 to the discharge position. After the roller has passed from engagement with the arm 74, the receptacle 22 will automatically swing to the filling position, and the weight 33 will cause the bar 32 to swing the frame 26 upwardly, and with it the receptacle 22. These parts will retain these last named positions until the rock shaft 52 has been again oscillated to effect the discharge into the receptacle 22 of another drink. When the roller 60 swings the arm 58 counter-clockwise, as viewed in Fig. 10, the valve stem 46 will be turned to the open position by means of the crank arm 51, plates 50 and 48 and crank 47, thus permitting carbonated water to be discharged through the conductor pipe 44 into the receptacle 22.

When the rock shaft 52 is rocked clockwise, Fig. 10, by the continued revolution of the crank arm 61 and roller 60, the valve stem 46 will be turned to the closed position. The rotary shaft 62, crank arm 61 and roller 60 come to a rest, as will be hereinafter described, after the rock shaft has been rocked counter clockwise, as described, and

before said rock shaft is rocked clockwise, to permit the discharge into the receptacle 22 of the proper amount of carbonated water.

Immediately upon the rock shaft 52 being rocked counter-clockwise, Fig. 10, the syrup ingredient is discharged from the syrup containing tank 13, Fig. 5, into the receptacle 22 and the carbonated water begins to pass into the receptacle 22, as described. When sufficient carbonated water has passed into the receptacle 22 to cause the weight of the latter, the drink content thereof, and the frame 26 to over balance the rod or bar 32 and the weight 33, the frame 26 and receptacle 22 will lower, thus raising the bar 32 and weight 33 and holding them elevated until the receptacle 22 has been tilted and the drink discharged therefrom into the waiting cup 15 on the bottom of the cup receptacle 16.

After the rock shaft 52 has been rocked counter-clockwise, Fig. 10, the motor circuit is broken, at which the motor shaft 69 stops, and is stationary until the frame 26 and receptacle 22 lowers, as described, upon which an arm 75 secured to the frame 26, Fig. 3 and Fig. 11 causes the motor circuit to be again closed, as will be described. At this time the shaft 62, and crank arm 61 will have made a half revolution from the initial position, shown in solid lines in Fig. 10, and will be in the dotted position shown in said figure, thus holding the arm 58 in the dotted position of Fig. 10.

When the arm 75 closes the motor circuit, the motor effects the revolution of the shaft 62, so that the roller 60 will engage the crank arm 59 and will thus rock the rock shaft 52 clockwise causing the valve stem 46 to turn to the closed position, thus shutting off the discharge of carbonated water, at which time the discharge of syrup will have stopped.

Now will be described the mechanism for supplying the syrup to the receptacle 22, by the rocking of the shaft 52 counter-clockwise, Fig. 10.

Referring to Figs. 1, 3, 5, 6, 8 and 9, 76 designates a conductor, the upper end of which is secured to the bottom of the tank 13, which contains the syrup, Figs. 1 and 5, the lower end of the conductor being secured to and discharging into a valve casting 77, Figs. 8 and 9, said valve casting having a vertical cylindrical portion 78 in which is vertically reciprocative a piston valve 79, which normally rests at the bottom of the portion 78, as in Fig. 8. This piston valve 79 has a vertical stem 80, which extends through and is slidable in the bottom of the cylindrical portion 78. A packing ring 81 may encircle the stem 80 and be fitted on a threaded stem 82 at the bottom of the portion 78. The stem 80 is reciprocated by a bar 83, Fig. 6, pivoted to an arm 84 secured to the

plate 30. The bar 83 is pivoted to a link 85 the upper end of which is pivoted to the lower end of the stem 80. The bar 83 has a longitudinal slot 86 in which is slidably fitted a pin 87 secured to a crank arm 88, which is secured on the rock shaft 52, Figs. 3 and 6.

When the rock shaft 52 is rocked counter-clockwise, from its initial position the piston 10 valve 79 will be forced upwardly, by the mechanism just described, past a passage 89 in the casing 77, which passage inclines downwardly from the cylindrical portion 78, thus shutting off the flow of syrup from 15 said cylindrical portion 78 to the passage 89. The lower end of the latter discharges into a vertical cylinder 90, the upper end of which is secured to the inclined portion 20 of the casing 77 which contains the passage 89.

Slidable on the cylinder 90 is a sleeve 91, to the periphery of which are attached two arms 92 of a plate 93 on which is fastened a valve 94, which is adapted, as shown in 25 Fig. 8, to seat against the lower end of the cylinder 90 to close the lower end of the latter.

To normally hold the valve 94 closed, there is provided a substantially horizontal lever 30 95, Figs. 8 and 9, which at one end carries a weight 96, which is adjustable on the lever 95 to which it may be secured in an adjusted position by a screw 97. The other end of the lever 95 has two arms 98 pivoted on a horizontal axis to a link 99 the upper end of which is pivoted to a ring 100, which encircles and is rigidly fastened to the cylinder 90. The outer ends 35 of the arms 98 are respectively disposed at opposite sides of the cylinder 90 and respectively pass between two pairs of pins 100' extending laterally from and respectively secured to opposite sides of the sleeve 91.

The valve stem 80 extends between the 40 arms 98, and has fastened on it, below the arms 98, a vertically adjustable ring 101, which carries a set screw 102 by which the ring is fastened on the rod to the position on which it may be adjusted.

When the valve 79 is moved upwardly to the closed position, above the passage 89, the stem 80 will cause the ring 101 to engage the lower edges of the arms 98, thereby 45 forcing the sleeve 91 downwardly, thus carrying the valve 94 downwardly to the open position, thereby discharging the syrup which is in the cylinder 90 and in the casing 77 below the valve 79. This action will 50 take place when the motor operated crank arm 61 causes the roller 60 to engage the crank arm 58 and rock the rock shaft 52 counter-clockwise, as before described.

When the crank arm 61 so rocks the rock 55 shaft, the latter will, through the crank arm

88, and mechanism connected with it and already described, lift the valve stem 80 and valve 79 to the closed position.

When the crank arm 61 again starts revolving, after the proper amount of drink 70 material has been discharged into the receptacle 22, and engages the crank arm 59 to rock the rock shaft 52 clockwise, the latter, through the mechanism already described and the crank arms 51 and 88 attached to the 75 rock shaft, will cause the valve stems 46 and 80 to be moved to the closed positions respectively. Then, as already described, the crank arm 61 through the roller 60 and arm 74 will tilt the receptacle 22 to the discharge 80 position, shown in solid lines in Fig. 6, and also in Fig. 3.

In order that the cup releasing lever 17 may be moved rearwardly to drop a cup 15 onto the bottom of the cup receptacle 16, 85 before the receptacle 22 is tilted to the discharge position, the lever 17 has attached to it a rod 103, Figs. 3 and 6, which is pivoted to a crank arm 104, Figs. 1, 3 and 6, fastened to the rock shaft 52. When the latter rocks 90 counter-clockwise, Fig. 10, the lever 17 will be swung to release and drop a cup 15, and when the rock shaft 52 is rocked in the opposite direction, the lever 17 will be swung so as to place the next succeeding cup in 95 condition to be dropped upon the next rearward swinging of the lever 17, in any manner usually performed by ordinary cup dropping mechanisms of this type.

The mechanism which times and controls 100 the opening and closing of the motor circuit, and consequently the rocking of the rock shaft 52 and the functions effected by it, will now be described.

Referring particularly to Figs. 2, 3, 11 105 and 12, supported on the front channel bar 31, is a vertical plate 105, which is parallel with the right side of the casing 1 and is disposed over the chute 7. Spaced from the plate 105 and rotatable on a shouldered 110 screw 106 mounted in said plate is a disk 107, which has a peripheral shoulder 108 disposed so as to be engaged by a plate 109, which is pivoted on a shouldered screw 110 mounted in the plate 105, and which has 115 fastened to it a spring 111, which is also secured to two screws 112 mounted in the plate 105. The tension of said spring normally forces the plate 109 into engagement with the disk 107. The plate 109 has also 120 secured to it a plate 113 the front end of which extends into the coin chute 4 through an opening 114 in the rear side of said chute. Said plate 113 is adapted to be engaged by and swung downwardly with the plate 109 by a proper coin passing downwardly through the chute, said coin having sufficient weight to overcome the tension of the spring 111 and the pressure of the shoulder 108. The plate 113 is below and in 125

the path of movement of the arm 75, which is attached to the frame 26, and is also adapted to be depressed by the arm 75 so as to release the disk 107 from the plate 109, when said frame and receptacle 22 lowers, due to the weight of a drink which has been discharged into said receptacle.

Encircling the screw 106 is a convolute spring 115, one end of which is attached to the disk 107, its other end being attached to the plate 105. The tension of the spring 115 is such as to normally turn the disk 107 clockwise, as viewed in Fig. 11, so as to bring the shoulder 108 into engagement with 15 the ratchet pawl or plate 109.

The disk 107 carries a pin 116 adapted to engage the upper edge of a lever 117 adjacent to the forward end of the latter. Said lever 117 is pivoted on a shouldered screw 118 mounted in the plate 105, and it has pivoted to it near its rear end a link 118', which is pivoted to a vertically movable contact bar 119, which is pivoted to a plate 120 mounted on a block of insulation 25 121 fastened to the plate 105. The latter carries a plate 122 to which is secured a contact 123 adapted to be struck by a contact 124 carried by the contact bar 119, to close at this point the motor circuit.

30 The lever 119 and plates 120 and 122 are electrically conductive.

For swinging the lever 119 to bring the contacts 123 and 124 together to close the motor circuit, when the disk 107 is released 35 from the pawl plate 109, and the lever 119 is thereby released from the pin 116, a coil spring 125 has its lower end attached to the lever 117 forward of the pivot screw 118, its other end being attached to a screw 126' mounted in the plate 105.

When either a coin dropped through the chute 4, or the arm 75 depresses the plate 113, the plate 109 will release the shoulder 108, and the spring 115 will turn the disk 45 107 to release the lever 117, upon which the spring 125 will swing the lever 117 so as to bring the contact 124 against the contact 123, by means of the link 118' and the bar 119.

50 The circuit will be closed at the contacts 123 and 124, and the motor 70 controlled thereby will continue to run until the disk 107 has been reset to its initial position, shown in Fig. 11. To reset said disk 107, there is mounted on a screw 126 a bell crank lever one arm 127 of which has a slot 55 through which extends a shouldered screw 128 mounted in the disk 107. When the other arm 129 of the bell crank lever is forced forwardly sufficiently, the disk 107 will be retracted counter-clockwise to its initial position, shown in Fig. 11, where it will be held by the pawl plate 109.

65 The disk 107 on being reset will cause the contacts 124 and 123 to be separated to break

the circuit, by means of the mechanism which has been described.

The bell crank lever is operated to reset the disk 107 by the motor 70 through the intervention of the following described 70 mechanism.

Fastened to the shaft 62, which is rotated by power supplied from the motor 70 through mechanism already described, is a 75 plate 130 which carries two diametrically opposite pins 131 and 132, which are adapted to be consecutively brought into engagement with a pin 133 mounted in a forwardly and backwardly slidable plate 134 horizontally mounted on a standard 135, fastened to the plate 105, and between the plate 105 and a guide plate 136 mounted on the standard 135.

The shaft 62 is revolved counter-clockwise, as viewed in Fig. 11, by the motor, so that when the pins 131 and 132 engage the 85 pin 133, the plate 134 will be forced forwardly so as to have its forward end engage the arm 129 of the bell crank lever, thereby swinging said lever to reset the disk 107. After either of the pins 131 or 132 has 90 passed, in the revolution of the plate 130 which carries the pins, out of engagement with the pin 133, the plate 134 will be retracted to its initial position, shown in Fig. 11, by a coil spring 137, one end of which is fastened to a screw 138 mounted in the standard 135, and the other end of which is fastened to a screw 139 mounted in the plate 134 forward of the screw 138.

When a purchaser places a proper coin in 100 the coin receiver 3 and forces the coin into the chute 4, the coin in passing through the chute 4 will strike and tip the plate 113, Fig. 11, and will then pass the plate and drop into the box 37, Figs. 1 and 2. The tipping of the plate 113 will swing the pawl 109 away from the shoulder 108, upon which the spring 115 will revolve the disk 107 to release the lever 117, thus closing the motor circuit, as has been described, through the contacts 123 and 124, and the bell crank lever will have its arm 129 brought against the front end of the slide plate 134.

When the motor circuit is first closed, the shaft 62 and plate 130 will be in the positions shown in Fig. 11, and the crank arm 61, which oscillates the rock shaft 52, will be in the position shown in solid lines in Fig. 10.

When the motor starts in its initial movement, the shaft 62 will be revolved in the direction indicated by the arrow, Fig. 11, and the pin 132 will engage the pin 133, thus sliding the plate 134 to reset the disk 107 and separate the contacts 123 and 124. At 120 the same time the rotation of the shaft 62 will start the roller 60 on its journey toward the arm 58, Fig. 10. In order to keep the motor 70 running until the shaft 62 has 125 made a half revolution, and the crank arm 130

61 has turned to the position shown in dotted lines in Fig. 10, thereby rocking the shaft 52 so as to drop a cup, close the valve 79 and open the valves 94 and 46, to effect the discharge of syrup and carbonated water into the receptacle 22, the shaft 62 has secured to it a disk 140, Fig. 11, having two peripheral arcuate cam surfaces 141 and 142, and between said surfaces two peripheral recesses 143 and 144.

5 A lever 145 pivoted on a horizontal axis on a standard 146, supported by the bracket 56, has mounted on its front end a roller 147, which is adapted to run on the periphery of the cam disk 140, Figs. 2, 3 and 11, the other end of the lever 145 being pivoted to the upper end of vertical member 148 carrying insulation 149 to which is attached a spring contact plate 150, mounted at one end on a block of insulation 151, Fig. 3, supported by the bracket 56. The contact plate 150 is adapted to be forced by the lever 145 against a spring plate 152 mounted on a conducting plate 153, Figs. 3 and 11, which 20 is mounted on the insulation block 151.

15 The motor circuit is shown in Fig. 4. One brush of the motor 70 is connected by a conductor 154 with the feed wire 155 of a lighting or power system. The other brush is 30 connected by a conductor 156 with the contact carrying plates 152 and 122. A conductor 157 connects the return wire 158 of the system with the contact plate 150 and the plate 120.

35 When the contacts 123 and 124 are in contact with each other, the current will pass from the feed wire 155, thence through the conductor 154, motor 70, conductor 156, plate 122, contact 123, contact 124, bar 119, 40 plate 120 and conductor 157 to the wire 158.

45 To keep the motor 70 supplied with current, after the contacts 123 and 124 have been separated, and to enable the motor to cause the shaft 62 to make a full half revolution, the contact plates 150 and 152 are brought together before the contacts 123 and 124 have been separated by the cam surface 141 engaging the roller 147 and swinging the lever 145 to force the plate 150 against 50 the contact plate 152. The motor 70 will thus continue running until the roller 147 enters the recess 144, at which time the spring contact plate 150 will separate from the contact plate 152, and the motor 70 will 55 stop after having revolved the shaft 62 half a revolution, and leaving the rock shaft 52 in the filling position, with the crank arms 61 and 58 as shown in dotted lines in Fig. 10.

60 The roller 60 in the turning of the shaft 62 will disengage from the arm 74, Figs. 3 and 10, thus permitting the receptacle 22 to drop to the filling position shown in dotted lines in Fig. 6. The valves 94 and 46 will have been opened, thus permitting the syrup 65 and carbonated water to be discharged into

the receptacle 22, the valve 79 will have been closed, Fig. 6, and the lever 17 will have been swung to drop a cup 15 to the position shown in Fig. 6, as has been described.

When enough carbonated water has been 70 discharged into the receptacle 22 to overbalance the weight 32, the frame 26 will lower, thus forcing the arm 75 downwardly into engagement with the plate 113, Fig. 11, and causing the said plate to move downwardly, thus freeing the disk 107 from the plate 109, upon which the contacts 123 and 124 will again be brought into contact, as described, and the motor 70 will be started. 75

When the motor again starts, the shaft 62 80 will revolve the crank arm 61 from the position shown in dotted lines in Fig. 10 to the position shown in solid lines in that figure. In the continued revolution of the arm 61, the roller 60 will first engage the crank 85 arm 59, rocking it from the dotted position in Fig. 10 to the position shown in solid lines, thus rocking the rock shaft 52 clockwise and effecting the closing of the valves 46 and 94 and the opening of the valve 79, thereby shutting off the discharge of carbonated water into the receptacle 22, and permitting the next charge of syrup to fill the casing 77 and cylinder 90, Fig. 8. 90

95 After this has been done, the continued turning of the crank arm 61 to its initial position will cause the roller 60 to leave the crank arm 59 and to engage the under side of the arm 74, of the receptacle 22, Fig. 10, thus tilting the receptacle 22 to the discharge 100 position shown in Figs. 3 and 6, and filling the cup 15 which is on the bottom of the cup receptacle 16, Fig. 6. The purchaser of the drink then removes the cup through the opening 9, and returns the cup, after having drunk the contents thereof, in to casing 105 1 through the opening 5.

When the contacts 123 and 124 are brought together the second time, the first time having been effected by the coin, and the second 110 time by the arm 75 of the frame 26, the roller 147 will pass out of the recess 144 and onto the cam surface 142, thus tilting the lever 145 to bring the contact plate 150 into contact with the plate 152 before the contacts 115 123 and 124 are again separated. The motor 70 will thus continue running until the roller 147 passes again into the recess 143, upon which the spring contact plate 150 will separate from the contact plate 152, and the 120 motor 70 will stop, with the parts all returned to their original initial positions occupied by them before a coin was inserted in the chute 4.

125 By the use of the cam controlled switches, the operation of the motor 70 and the proper positioning of the different parts at the proper times are positively and accurately effected.

130 In apparatus of this character it has been

found difficult to always withdraw, from the supply, drinks of uniform quantity. It has also been found to be difficult to always provide the proper and uniform quantity of syrup for a drink. With the use of the method of obtaining the quantity of a drink by the employment of a controlling weight, my apparatus will always provide drinks of substantially uniform quantity.

- 10 In my apparatus, to prevent air pockets forming in the syrup measuring mechanism, which would interfere with the proper measuring of the syrup ingredient, the cylinder 90 is of relatively wide diameter, and the 15 passage 89, Fig. 8, is upwardly inclined therefrom. With this construction, when the valve 79 is open, the syrup will pass downwardly from the conductor 76 into the cylinder 78, thence downwardly on the lower 20 side of the passage 89 into the cylinder 90, and the air, which is in the cylinder 90, will pass along the upper side of the inclined passage 89 into the vertical cylinder 78, and from there will bubble upwardly into the 25 syrup tank 13 through the conductor 76, so that no air pockets will form and the cylinder 78, above the lowered valve 79, the passage 89 and the cylinder 90, will completely fill with syrup, thereby always measuring 30 uniform quantities of the syrup content of the drinks dispensed. Also by reason of the relatively large diameter of the cylinder 90 and the inclination upwardly of the passage 89, the contents of syrup under the valve 79, 35 when the latter is closed will be almost instantaneously discharged into the receptacle 22 and replaced by air.

As shown in Figs. 1, 2 and 5, the ice tank 11 may be provided at its bottom with a 10 valved drain pipe 158.

I do not limit my invention to the structure shown and described, as many modifications, within the scope of the appended claims, may be made without departing from the spirit of my invention.

What I claim is:—

1. In a vending apparatus, a support, a frame pivoted thereto, counterbalancing means at one side of the axis of said frame, 50 a receptacle for the substance vended pivoted to said frame at the other side of said axis, means for discharging said substance into said receptacle, an electric circuit including a motor and circuit controlling means, means actuated by said motor for controlling said discharge means and for tilting said receptacle to the discharge position, coin controlled means for operating said circuit controlling means to close 55 said circuit, and means actuated by said frame, when the latter is swung by the weight of said receptacle and the contents thereof for operating said circuit controlling means.

65 2. In a vending apparatus, an upwardly

and downwardly movable support, a receptacle for the substance vended pivoted to said support, counterbalancing means normally lifting said support and receptacle, the weight of said receptacle and a predetermined amount of said substance in said receptacle effecting the lowering of said support, an electric circuit including a motor and circuit controlling means, means actuated by said motor for controlling the discharge of the vended substance into said receptacle and for tilting said receptacle to the discharge position, coin actuated means for initially operating the circuit controlling means to close the circuit to permit the motor to effect the discharge of the vended substance into said receptacle, and means actuated by the lowering of said support for actuating said coin actuated means to operate said circuit controlling means to close the circuit to permit the motor to shut off the discharge of the vended substance into said receptacle and to then effect the tilting of the receptacle to the discharge position.

3. In a vending apparatus, an upwardly and downwardly movable support, a receptacle for the substance vended movable thereon to and from a discharge position, counterbalancing means for normally lifting said support to an elevated position, 95 said receptacle, when containing a predetermined amount of the vended material effecting the lowering of said support, means for controlling discharge of the substance into said receptacle, a rotary driven shaft, motor operated means by which said shaft is revolved part of a revolution and then stopped, means by which when said shaft revolves said part of a revolution said controlling means will be operated to discharge said substance into said receptacle, means actuated by the lowering of said receptacle for causing the motor operated means to actuate said controlling means for shutting off the discharge of said substance into said receptacle, and means by which when said shaft makes the remainder of a revolution, the receptacle will be moved to a discharge position.

4. In a vending apparatus, an upwardly and downwardly movable support, a receptacle movable thereon to and from a discharge position, counterbalancing means for normally moving said support to an elevated position, said receptacle, when containing a predetermined amount of substance to be vended effecting the lowering of said support, a conductor including a valve discharging into said receptacle, a rotary driven member, an electric circuit including a motor and circuit controlling means, means actuated by said motor for rotating said driven member, means operated by said driven member during one half a revolution 125 thereof for opening said valve, and during 130

- the next half revolution to close said valve and move said receptacle to the discharge position, and means actuated by the lowering of said support for operating the circuit controlling means to close the circuit.
5. In a vending apparatus, a support, a dispensing receptacle pivoted thereon to swing to a liquid receiving position and to a liquid discharge position, a rotary driven member, a conductor having a valve and disposed so as to discharge into said receptacle, and means actuated by said driven member by which the valve will be opened, then closed and the receptacle then tilted 15 to a discharge position.
6. In a vending apparatus, an upwardly and downwardly movable support, a dispensing receptacle pivoted thereon to swing to a receiving position and to a discharge position, counterbalancing means for said support for raising the support when the receptacle is empty, the latter when containing a predetermined amount of liquid effecting the lowering of said support, a rotary driven member, a conductor having a valve and disposed so as to discharge into said receptacle, a motor, means actuated by said motor for revolving said driven member, motor controlling means by which the motor is started 30 and permitted to revolve the driven member half a revolution and the motor then stopped, means actuated by said driven member during said half revolution for opening said valve, and during the next half revolution effecting the closing of said valve and the tilting of said receptacle to the discharge position, and means actuated by the lowering of said support for actuating the motor controlling means to start the motor 35 after its stopping following the first half revolution.
7. In a vending apparatus, a support tilt-able on a horizontal axis, a dispensing receptacle pivoted thereon on a horizontal axis, motor controlled means for effecting discharge of liquid into said receptacle and for tilting said receptacle to the discharge position, and means controlled by the swinging of said support for controlling the 40 operation of said motor controlled means.
8. In a vending apparatus, a support pivoted on a horizontal axis, a dispensing receptacle pivoted thereon on a horizontal axis at one side of the axis of said support, a counterbalancing means for said support at the other side of the axis of said support, a conductor having a valve and disposed so as to discharge into said receptacle, motor controlled means for opening and closing 45 said valve and for controlling the tilting of said receptacle to the receiving and discharge positions, and means actuated by the lowering of said support with said receptacle for controlling the operation of said motor 50 controlled means.
9. In a vending apparatus, a tiltable support, a dispensing receptacle pivoted thereon, a conductor having a valve and disposed so as to discharge into said receptacle, motor operated means for effecting the opening 70 and closing of said valve and for controlling the tilting of said receptacle to the receiving and discharging positions, and means actuated by the swinging of said support for controlling the operation of said motor operated 75 means.
10. In a vending apparatus, an upwardly and downwardly movable support, a dispensing receptacle pivoted thereon to swing to a receiving position and to a discharge 80 position, a conductor having a valve and disposed so as to discharge into said receptacle, a rock shaft, a rotary driven member, motor actuated means for rotating said driven member, means actuated by said driven member for rocking said rock shaft and for tilting said receptacle to the discharge position, means actuated by said rock shaft for opening and closing said valve, and means actuated by the lowering of said 85 support for controlling the operation of said motor actuated means.
11. In a vending apparatus, a pivoted support having a horizontal axis, a dispensing receptacle pivoted thereon on a horizontal 90 axis at one side of the axis of said support, a rod fastened to said support, a counterbalance weight carried by said rod at the other side of said axis of said support, motor operated means for effecting the discharge of liquid into said receptacle and for controlling the tilting of said receptacle to the receiving and discharge positions, and means actuated by said support for controlling the 95 operation of said motor operated means.
12. In a vending apparatus, a support pivoted on a horizontal axis, a dispensing apparatus pivoted thereon at one side of said axis so as to swing to and from the discharge position, a rod carried by said support, a weight adjustable on said rod at the other side of said axis toward and from said axis, motor operated means for effecting the discharge of liquid into said receptacle and for controlling the tilting of said receptacle to 100 and from the discharge and receiving positions, and means actuated by the lowering of said support for controlling said motor operated means.
13. In a vending apparatus, a support pivoted on a horizontal axis, a dispensing receptacle pivoted thereon to swing at one side of said axis to and from the discharge and receiving positions a weight carried by said support at the other side of said axis, two conductors disposed so as to discharge into said receptacle, one having a pair of valves, the other having a single valve, motor operated means for opening and closing said valves and arranged to open one of said pair of valves 105 110 115 120 125 130

- while closing the other valve of the pair, and for controlling the tilting of said receptacle, and means actuated by the lowering of said receptacle and said support for controlling said motor operated means.
14. In a vending apparatus, a support, a dispensing receptacle pivoted thereon to swing to receiving and discharge positions, means for discharging liquid into said receptacle, a rock shaft, means actuated by said rock shaft for controlling the discharge of liquid into said receptacle by said discharge means, a motor actuated rotary driven shaft, and means actuated by said rotary shaft for rocking said rock shaft and for controlling the tilting of said receptacle to said two positions.
15. In a vending apparatus, a support pivoted on a horizontal axis, a dispensing receptacle carried thereby and movable to receiving and discharging positions, means for discharging liquid into said receptacle, a rock shaft, means actuated by said rock shaft for controlling said liquid discharge means, a weight carried by said support at the side of the axis of the latter opposite to the said receptacle and adjustable toward and from said axis, motor actuated means for rocking said shaft and for controlling the movement of said receptacle on said support to said two positions, and means controlled by the movement of said support for controlling the operation of said motor actuated means.
16. In a vending apparatus, a support pivoted on a horizontal axis, a receptacle for substance to be vended movable on said support at one side of the axis of the latter to and from receiving and discharge positions, a weight carried by said support at the other side of said axis and adjustable toward and from said axis, means for discharging liquid into said receptacle, a rock shaft having a crank-means actuated by said rock shaft for controlling said discharging means, a motor driven rotary shaft, means actuated by said rotary shaft for rocking said crank to and fro and for controlling the tilting of said receptacle to and from the discharge positions, and means actuated by said support for controlling the operation of said rotary shaft.
17. In a vending apparatus, a vertically movable support, a dispensing receptacle tiltable thereon to and from a discharge position, means for discharging material to be vended into said receptacle, counterbalancing means for said support by which the latter is normally lifted, and which, when a predetermined weight of material to be vended is discharged into said receptacle, permits the said support to lower, and means controlled by said support in lowering for actuating said discharging means to stop the discharge of said material into said receptacle and for tilting said receptacle to the discharge position.
18. In a vending apparatus, a vertically movable support, a dispensing receptacle tiltable thereon to and from a discharge position, means for discharging material to be vended into said receptacle, counterbalancing means for said support by which the latter is normally lifted, and which, when a predetermined weight of said material is discharged into said receptacle, permits the support to lower, a motor, motor controlling and operating means, motor actuated means by which, when the motor is operated, the motor actuated means first effects the opening of said discharge means and then actuates said motor controlling means to stop the motor, and means actuated by the lowering of said support for actuating the motor controlling means to operate the motor and thereby cause said motor actuated means to close said discharging means and tilt said receptacle to the discharge position.
19. In a vending apparatus, a vertically movable support, a dispensing receptacle tiltable thereon to and from a discharge position, means for discharging material to be vended into said receptacle, counterbalancing means which normally lifts said support and which permits said support to lower when a pre-determined weight of said material has been discharged into said receptacle, a rotary shaft, means for rotating said shaft step by step, means by which said shaft first opens said discharging means and then closes said discharging means and tilts said receptacle to the discharge position, and means actuated by said support in lowering for controlling said shaft rotating means.
20. In a vending apparatus, a vertically movable support, a dispensing receptacle movable thereon to and from a discharge position, means for discharging material to be vended into said receptacle, counterbalancing means which normally lifts said support and permits the support to lower when a pre-determined weight of material has been discharged into said receptacle, a rock shaft, means by which when said shaft is rocked in one direction said discharging means will be opened and when said shaft is rocked in the opposite direction said discharging means will be closed, means for oscillating said rock shaft, means actuated by said support in lowering for controlling said oscillating means, and means actuated by said oscillating means for moving said receptacle to the discharge position after said discharging means has closed.
21. In a vending apparatus, a vertically movable support, a dispensing receptacle carried by said support and having discharging means, means for discharging material to be vended into said receptacle, counterbalancing means which normally

- lifts said support and permits said support to lower when a predetermined weight of said material has been discharged into said receptacle, operating means by which 5 said material discharging means last named is opened and then closed and by which said receptacle discharging means is opened after the closing of the other discharging means, and means actuated by said 10 receptacle in lowering which controls the operation of said operating means.
22. In a vending apparatus, a dispensing receptacle for material to be vended, a motor, motor operating means, motor actuated 15 means, means operated by said motor actuated means for effecting discharge of said material into said receptacle and for effecting discharge of material from said receptacle, means actuated by said motor actuated 20 means for controlling said motor operating means, and means actuated by said receptacle after a pre-determined weight of material has been discharged into said receptacle for controlling the said motor operating 25 means.
23. In a vending apparatus, a dispensing receptacle for material to be vended having discharging means, means for discharging said material into said receptacle, an electric 30 circuit including a motor and circuit controlling means, means actuated by said motor for controlling both of said discharging means, means actuated by said motor actuated 35 means for operating said circuit controlling means to close said circuit, and means actuated by said receptacle after a pre-determined weight of material has been discharged into said receptacle for operating said circuit controlling means to close said 40 circuit.
24. In a vending apparatus, a dispensing receptacle for material to be vended having discharging means, means for discharging said material into said receptacle, an electric 45 circuit including a motor and circuit controlling means comprising two circuit closers having each means for being normally opened, means actuated by said motor for operating both of said discharging 50 means, means actuated by said motor actuated means for operating one of said circuit closers to close said circuit, and means actuated by said receptacle after a pre-determined weight of said material has been dis- charged into said receptacle for operating the other circuit closer to close said circuit.
25. In a vending apparatus, a vertically movable support, a dispensing receptacle tiltable on said support to and from a discharge position, means for discharging material to be vended into said receptacle, a rock shaft, a rotary shaft having a crank arm arranged to oscillate said rock shaft, means actuated by said rock shaft for opening and closing said discharging means, 60 means actuated by said crank arm for tilting said receptacle to the discharge position after said discharging means has been closed, counterbalancing means for normally lifting said support and which permits lowering of said receptacle when a pre-determined weight of said material has been discharged into said receptacle, an electric circuit including a motor and normally open circuit closing means, means actuated by 65 said motor for rotating said rotary shaft, means actuated by said rotary shaft for closing said circuit closing means, and means actuated by said support in lowering for closing said circuit closing means.
26. In a vending apparatus, a vertically movable dispensing receptacle, means for normally lifting said receptacle having an arm, counter balancing means for elevating said lifting means which permits said lifting means to lower when a pre-determined weight of material to be vended has been discharged into said receptacle, a rotary shaft, means actuated by said shaft for controlling the discharge into said receptacle 70 of said material and the discharge therefrom of said material, an electric circuit including a motor and two circuit closers one of which has means for normally holding it open, the other having means for 75 being normally forced to the closed position, detent means for holding the last named circuit closer open, an operating member releasable by said arm for holding said detent means in the holding position, 80 means actuated by said shaft for forcing said detent means to the holding position, and means actuated by said shaft for closing said first named circuit closer.
- In testimony whereof I have signed my 85 name to this specification.

OREN F. ROBERTS.
